(57) **CLAIM**

The ornamental design for a portable magnetic charger for smartwatch, as shown and described.

DESCRIPTION

FIG. 1 is a perspective view of a portable magnetic charger for smartwatch showing our new design;
 FIG. 2 is a front elevational view thereof;
 FIG. 3 is a back elevational view thereof;
 FIG. 4 is a left side elevational view thereof;
 FIG. 5 is a right side elevational view thereof;
 FIG. 6 is a top plan view thereof;
 FIG. 7 is a bottom plan view thereof; and,
 FIG. 8 is a perspective view thereof, showing a cap being pulled out.

The broken lines in the figures illustrate portions of the portable magnetic charger for smartwatch that form no part of the claimed design.
